UNITED STATES PATENT OFFICE.

WALTER A. KEITH, OF LOS ANGELES, CALIFORNIA.

FLANGE-OILER.

1,182,382.

Specification of Letters Patent.

Patented May 9, 1916.

Application filed September 30, 1914. Serial No. 864,242.

To all whom it may concern:

Be it known that I, WALTER A. KEITH, a citizen of the United States, residing at Los Angeles, in the county of Los Angeles and State of California, have invented a new and useful Flange-Oiler, of which the following is a specification:

The primary object of the invention is to provide an automatic flange oiler operable with any hard grease, and spraying the grease when properly melted directly against a wheel flange.

Another object of the invention is to provide a flange oiler which will make it possible to spray a car wheel with a soapy solution of water and grease, so as to keep the flange of the wheel clean from all particles of sand, grit and other extraneous matter.

With these and other objects in view, the invention consists in certain novel features of construction, combination, and arrangement of parts, as will be hereinafter fully described, claimed and illustrated.

Referring to the drawings: Figure 1 designates a side elevation of my flange oiler, showing the same in operative position on a locomotive. Fig. 2 is a top plan view of the flange oiler. Fig. 3 is an enlarged side elevation partly in section of the flange oiler. Fig. 4 is an elevation showing the manner of securing the casing top in position.

Referring in detail to the drawings, by numerals, 1 designates a cylindrical casing or condensing chamber having an intake or opening 2, and a discharge opening 3. The top end of the container is closed by a clamp or cover 4 rigidly secured to a spring pressed rod 5 sliding between guides 6, 7 and 8. The coil spring 9 encircles that portion of the rod 5 between the guides 7 and 8, and its lower end engages a cross pin 10 so as to hold the rod normally in its lowermost position, and thus clamp the cover firmly. When it is desired to open the casing 1, the rod may be sprung upwardly and then rotated in the guides so as to swing the cover from over the casing. The casing may be secured to any suitable portion of a locomotive by any desired means such as a bracket 11.

Within the casing 1 is a removable cylindrical container 12 made of any suitable perforated material and having a conical bottom 13. The container may be of a somewhat larger diameter than the casing 1, as best shown in Fig. 3, and is open at its up-

per end so as to be filled with a suitable lubricant such as hard grease.

An elbow 14 is connected in communication with the opening 3 and has its other end connected to a fitting 15 by a coupling or connecting member 16. The coupling 15 forms a swivel connection with a pipe 16, as indicated by the numeral 17, and said pipe 16 is connected to a T-coupling 18 in 65 the lower end of which is screwed or otherwise secured a delivery pipe 19, which is held always in engagement with the flange of the wheel, by means of a weight 20 connected to the upper end of the coupling 18 by an arm 21, and a screw 22 is provided to adjust the swivel joint 17. It will be noted that the feed line from the discharge port 3 to the delivery pipe 19 is so constructed as to permit this pipe to be turned and adjusted so as to project toward the wheel 75 23 at the desired angle. In practice, I find that it is best to have this pipe 19 running downwardly at approximately a 45 degree angle, and toward the flange 24 at approximately 80 a 45 degree angle, as shown in Figs. 2 and 3.

Any means suitable for the purpose may be employed for melting the grease and forcing the same through the supply pipe 85 19 into contact with the wheel flange. The preferred means, however, has been illustrated in the drawing where 25 designates the air pump exhaust pipe, 26 an oil trap which catches all the oil that is fed through 90 the pump for lubrication thereof, which amounts to about two or three drops per minute when the pump is working, and a pipe line 27 extending from the bottom of the oil trap to the opening 2 of the casing 1. 95 A cock 28 is provided to control the flow through the pipe line 27.

Steam entering the casing 1 impinges against the container 2 melting the grease therein. This grease, with the condensed 100 steam, runs downwardly into the delivery pipe 19, and is fed onto the flange 24 in the form of a hot soapy substance, which is admirably adapted for keeping the wheel flange clean, and reducing the wear on the 105 flanges and rails. The weight 20 holds the discharge end of the delivery pipe 19 always against the flange so that the fluid is properly distributed. It is a well known fact that the greatest wear on flanges and rails 110 comes when the engine or cars are descending grades and at this time the air pump

are always working at high speed to furnish air for braking purposes, so there is a correspondingly large amount of steam and oil passing through the pipe line 27 in casting 1, and thence to the delivery pipe 19, carrying with it some of the hard lubricant. On ascending grades or level track, the wear is not so great as on descending grades, and the operation of the pump is not so fast. Thus it will be seen that the preferred means which I have shown for melting the hard grease works automatically to supply grease in proportion to the frictional pressure on the flanges and rails. From the foregoing description taken in connection with the accompanying drawings, it will be seen that I have provided a very simple and practical automatic flange oiler, which is adapted for use on all kinds of rolling stock, and which is very economical, since it supplies grease in proportion to the wear on the flanges. It will be understood that while I have shown and described the preferred embodiment of my invention, that I do not wish to be limited to this exact construction, but may make such changes as may suggest themselves from time to time, provided they fall within the scope and spirit of the invention as claimed.

What I claim is:

1. The process of lubricating wheel flanges, which process comprises introducing steam around and into the periphery of a column of hard grease to melt some of the grease from said column to form a hot soapy

mixture of grease and water, and discharging said hot soapy mixture against the flanges to lubricate the flanges and wash them free from grit. 40

2. In a flange oiler, a delivery pipe, a swivel joint for said pipe, means for holding the discharge end of the pipe in contact with the flange of the wheel, and means for tightening or loosening the swivel joint. 45

3. In a flange oiler, a casing, a container in the casing and spaced apart therefrom adapted to contain hard grease, a delivery pipe, a pipe line between said delivery pipe and the container, and means for conveying steam to the interior of the container whereby the grease is melted to form a soapy solution. 50

4. A flange oiler including a cylindrical casing, a perforated container in said casing adapted to hold hard grease, the casing being formed with an intake opening and with a discharge opening, a steam pipe connected to the intake opening, a pipe line connected to the discharge opening, a delivery pipe, a swivel connection between the delivery pipe and the lower end of the discharge pipe, and a weight tending to swing the discharge end of the delivery pipe upwardly. 55

In testimony whereof, I have hereunto set my hand at Los Angeles, California, this 23rd day of September, 1914. 60 65

WALTER A. KEITH.

In presence of—

RODNEY M. SMITH,
LORA M. BOWERS.
